UNITED STATES PATENT OFFICE

HARRY B. HULL AND DONALD H. REEVES, OF DAYTON, OHIO, ASSIGNEES TO FRIGID-AIRE CORPORATION, OF DAYTON, OHIO, A CORPORATION OF DELAWARE

REFRIGERATING APPARATUS

Application filed February 27, 1928. Serial No. 257,227.

This invention relates to refrigerating apparatus and particularly to an improved construction of refrigerating element and its arrangement within a refrigerating cabinet.

5 One of the objects of the invention is to provide an improved refrigerating element particularly adapted for small cabinets, which will occupy a small amount of space.

Another object of the invention is to provide an improved refrigerating element of the dry expansion type which both freezes ice and cools a cabinet effectively.

Further objects and advantages of the present invention will be apparent from the 15 following description, reference being had to the accompanying drawings, wherein a preferred form of embodiment of the present invention is clearly shown.

In the drawings:

20 Fig. 1 is an elevation of a refrigerating cabinet showing a cooling unit constructed and arranged according to the present invention;

Fig. 2 is a front elevation on an enlarged scale of the refrigerating element;

Fig. 3 is a top plan view of the element partly broken away;

Fig. 4 is a side elevation of the element partly broken away; and

30 Figs. 5 and 6 are front elevations of the separate coils of refrigerating element before assembly.

It has heretofore been regarded as necessary to have refrigerating elements so placed in refrigerating cabinets of the household type that air can freely circulate over the entire surface of the refrigerating element.

To this end the element has been placed at a 40 considerable distance from the walls of the cabinets and baffles or partitions have been provided to direct the circulating air over the elements, a considerable space naturally being required between the element and baffle.

45 This has caused the amount of space devoted to the refrigerating element to be very large in proportion to the total volume of cabinet, and in the case of very small cabinets, such as those provided for apartment houses, the problem of space available for

the storage of food has become of increased importance.

One of the objects of our invention is to provide a refrigerating element which requires no baffle, and thus one which not only occupies a minimum volume itself but also requires the minimum amount of space to be devoted to air circulation over it when placed in the cabinet.

Referring particularly to Fig. 1, 10 designates a refrigerating cabinet of any suitable construction which has a door opening 11, a back wall 12, side walls 13, and a top wall 14. The side walls and top wall meet at corners, in one of which we place a refrigerating element 15 which may be supplied with liquid refrigerant by any suitable refrigerating apparatus not shown, and which may be for example of the type shown in the patent to

Osborn, No. 1,556,708, October 13, 1925. The 70 refrigerating element is disposed in the corner as close to the walls as construction and frosting conditions will permit. It is placed sufficiently close to the top wall effectively to prevent the free circulation of air over the element. In actual practice this distance may be

75 a half inch. We have found that where the air circulation between the element and the wall is effectively blocked, and where the frost which builds up on the unit is not allowed

80 actually to touch the walls, the element can be placed very close to the walls without noticeably increasing the amount of heat leakage thru the walls at this point. We have also found that the cooling element may be 85 closer to the top wall than to the side walls since the heat leakage in the downward direction thru the top wall is relatively small.

The refrigerating element includes a freezing compartment 19, (Fig. 2) to be more fully described herein and means projecting from the freezing compartment away from the walls into the cabinet for cooling the air in the cabinet and setting up circulation. As shown in Figs. 3 and 4 this means is preferably a 90 number of L-shaped fins 20 projecting below and to one side of the freezing compartment. The air may circulate freely between the fins, which are in intimate contact with the refrigerant and are chilled by it.

Beneath the refrigerating element is placed a defrosting pan 21, slidably supported on one of the food storage shelves 22 which is provided with a depression 23 serving as a 5 guide to insure the placing of the pan directly beneath the refrigerating element. When the refrigerating apparatus is operating the pan serves as a convenient storage for articles to be kept very cold, such as ice cubes, and 10 when the refrigerating element is being defrosted the pan serves to collect the water which drips from the element. Air chilled by the element sinks into the pan and overflows into the cabinet, likewise the air chilled 15 by the fins flows downwardly either into or around the pan and sets up the circulation of air which refrigerates the cabinet in the well known manner.

Figs. 2, 3 and 4 show in detail one form of 20 construction of the refrigerating element. This preferably includes an inner coil of tubing 25 which is of the form shown in Fig. 5 and an outer coil of tubing 26 which is of the form shown in Fig. 6. The refrigerant 25 coil or conduit 26 is open, that is, this coil is not insulated from the freezing coil or conduit 25 and the freezing compartments or sleeves 30 and 31. Within the coil 25 is placed a freezing compartment 30 to receive 30 a freezing container 31a. It has been found that the majority of the heat conducted away from such freezing containers in apparatus of this sort when freezing ice cubes for example, is conducted through the bottom of 35 the freezing container and freezing compartment to the refrigerant in the coil 25, and that water can be frozen more quickly by securing the freezing containers along the bottom to a refrigerant conduit than by attaching the conduit in any other manner. Therefore the bottom of the freezing compartment 30 is soldered to each convolution on the bottom of the coil. On top of the coil a second compartment 31 is placed, whose 40 bottom is soldered to each convolution. The compartments are adapted to receive freezing containers or ice trays 31a. The coil 25 and compartments 30 and 31 constitute the freezing compartment 19, referred to above. 45 The coil 26 is placed around the coil 25 and the two compartments, and is connected in series with the coil 25 by a connection 32 (Fig. 3). The two coils thus in effect form a single continuous conduit. One of the L-shaped fins 20 is soldered to the bottom and one side of each convolution of the coil 26, the latter being preferably formed of flattened tubing to provide a maximum amount 55 of flat surface to be soldered to the fins. The convolutions of the coil 26 are held in place by a number of braces 34, some of which are soldered to the fins and others to the convolutions as shown in Fig. 3. The braces are also 60 provided with portions 34a which are sol-

dered to the coil 25, thus positioning the two coils with respect to each other.

At the ends of the compartment beyond the coils are secured a pair of brackets 36 and 37 having feet 38 by which the refrigerating element is supported on the top wall of the cabinet. The front bracket 36 is slightly shorter than the rear bracket 37 in order that the compartments 30 and 31 may slope slightly from front to the rear and prevent accidental 70 sliding out of the ice trays 31a due to vibration or other causes. A cover or shield 40 is secured to the front of the compartments. This may be coated with vitreous enamel or 75 may be made of polished non-corroding metal such as Monel, in order to enhance the appearance of the cooling unit. The shield is provided with openings 41 and 42 registering 80 with the compartments 30 and 31 respectively to permit the insertion of the ice trays. 85 The rear bracket 37 is provided with a pair of lugs 43 and 44 which receive screws for attaching the expansion valve 50 which is provided for the purpose of controlling the supply of refrigerant to the refrigerating element. The particular construction of the valve forms no part of the present invention 90 and may be for example as shown in the application of Harry B. Hull, Serial No. 183,480, filed April 13, 1927. A thermostat 95 bulb 51 is secured to the back of the compartments by a clip 52 to control the refrigerating apparatus in response to the refrigerating demand.

It will be appreciated that a refrigerating 100 element must be of a given cross section in order to receive ice trays of a size which is regarded as essential in present-day practice. The necessary heat exchange surface for cooling small cabinets may then be made 105 on such a refrigerating element within a length considerably less than the depth of the cabinet. The element is therefore placed toward the front of the cabinet and the space between the end of the cabinet and the rear 110 wall is used for the expansion valve. Space at either end of the refrigerating element within its sides would ordinarily be inconvenient for the storage of food, because if this space be left at the front of the element 115 it should be left vacant to permit the withdrawal of ice trays, and if left at the back of the element it would be very difficult of access. It will therefore be appreciated that the refrigerating element provided occupies 120 the minimum space and leaves the maximum space in the cabinet for convenient food storage.

In dry expansion refrigerating elements of 125 this type the temperature of the refrigerant conduit or the amount of refrigeration per unit length which the conduit can supply varies along the length of the conduit, decreasing in the direction away from the expansion valve. The particular arrangement 130

employed in the construction of this refrigerating element permits the maximum freezing effect to be distributed thruout the element because both freezing compartments are connected alternately along the length of the coil 5, consequently the freezing effect of the coil is distributed equally between the two compartments. Moreover the coil is connected to the bottom of each compartment which is the most favorable position for freezing 10 articles within the compartments.

The coil 25 is designed to furnish sufficient refrigeration to freeze water in both compartments, and the coil 26 which surrounds the freezing compartments is intended primarily for cooling the circulating air. The device is preferably operated so that the entire coil 25 is flooded with liquid refrigerant. The coil 26 may or may not be entirely flooded. That is, when the apparatus is first assembled 20 the expansion valve is so adjusted that frost appears on the whole of the first coil 25 and the second coil 26 is frosted from its point of connection to the first coil 25 to some point intermediate its ends. The frost line or point 25 where the frosting on the coil stops indicates how much of the conduit is flooded. By properly proportioning the parts, the system may be operated so that the coil 26 and fins 30 do not remain coated with frost during the entire operation. It will be understood that the apparatus is periodically operated. During the operating periods frost may form on the entire evaporator, but due to the large 35 surface of fins exposed to the circulating air the fins can ordinarily be defrosted during the periods when the device is not circulating refrigerant. This leaves the fins bare for the subsequent operating period and enables the 40 transfer of the maximum amount of heat. The inner coil 25 can be completely coated with frost and remain frosted during the non-operating periods, and thus protect the ice within the compartment 19 from being melted 45 by the circulating air.

While the form of embodiment of the present invention as herein disclosed, constitutes a preferred form, it is to be understood that other forms might be adopted, all coming within the scope of the claims which 50 follow.

What is claimed is as follows:

1. Refrigerating apparatus comprising in combination, a cabinet having walls enclosing a compartment to be cooled, a pair of the walls forming a corner, and a refrigerating element disposed in the corner, the refrigerating element including means forming an enclosure for a freezing container out of contact with the walls but sufficiently close to one of them to prevent free circulation of air between the walls and the enclosure, and L-shaped fins projecting from the bottom and one side of the enclosure for cooling air in 60 the cabinet.

2. A refrigerating element for refrigerating apparatus adapted to be placed in the path of circulating air for cooling the air and for freezing ice, comprising in combination a refrigerant conduit, a pair of freezing sleeves disposed in vertical alignment, the outer side of the bottom of each sleeve being directly secured in intimate thermal contact with said conduit, and an open refrigerant conduit surrounding the first mentioned conduit and both sleeves to chill air circulating over said element to prevent absorption of heat by said air from the sleeves. 70

3. A refrigerating element for refrigerating apparatus adapted to be placed in the path of circulating air for cooling the air and for freezing ice, comprising in combination a refrigerant conduit, a pair of freezing sleeves disposed in vertical alignment, the outer side of the bottom of each sleeve being directly secured in intimate thermal contact with said conduit, and an open refrigerant conduit surrounding the first mentioned conduit and both sleeves, and connected in series with the first mentioned conduit to chill air circulating over said element to prevent absorption of heat by said air from the sleeves, and means for supplying refrigerant to the first mentioned conduit. 85

4. A refrigerating element for refrigerating apparatus adapted to be placed in the path of circulating air for cooling the air and for freezing ice, comprising in combination a coil of refrigerant conduit, a pair of freezing sleeves disposed in vertical alignment, the outer side of the bottom of each sleeve being directly secured in intimate thermal contact with said coil, and an open coil of refrigerant conduit surrounding the first mentioned coil and both sleeves to chill air circulating over said element to prevent absorption of heat by said air from the sleeves. 95

5. A refrigerating element comprising in combination, a horizontally disposed refrigerant conduit, a pair of horizontally extending freezing sleeves disposed in vertical alignment, said refrigerant conduit entirely surrounding the lower one of said pair of sleeves, the outer side of the bottom wall of each sleeve being directly secured in intimate thermal contact with said refrigerant conduit, and an open horizontally disposed refrigerant conduit surrounding the first mentioned conduit and both sleeves to chill air circulating over said element to prevent absorption of heat by said air from the sleeves. 100

6. A refrigerating element comprising in combination, a horizontally disposed refrigerant conduit, a pair of horizontally extending freezing sleeves disposed in vertical alignment, said refrigerant conduit entirely surrounding one of said sleeves, and being directly secured in intimate thermal contact with the outer side of the bottom wall of each sleeve, and an open horizontally dis- 115 120 125 130

posed refrigerant conduit surrounding the first mentioned conduit and both sleeves to chill air circulating over said element to prevent absorption of heat by said air from the 5 sleeves, and means for supplying refrigerant to the first mentioned conduit.

In testimony whereof we hereto affix our signatures.

10
